UNITED STATES PATENT OFFICE.

FRANK M. PRATHER, OF LOS ANGELES, CALIFORNIA.

PNEUMATIC POWER-TRANSMITTER.

1,098,300.

Specification of Letters Patent.

Patented May 26, 1914.

Application filed November 6, 1911. Serial No. 658,888.

To all whom it may concern:

Be it known that I, FRANK M. PRATHER, a citizen of the United States, residing at Los Angeles, in the county of Los Angeles and State of California, have invented a new and useful Pneumatic Power-Transmitter, of which the following is a specification.

This invention relates to pneumatic power transmitters of a type wherein a plurality of cylinders with pistons are employed, the cylinders being connected to the driven shaft and pistons to the driving shaft, such that upon a relative movement of both the driving shaft and driven shaft air would be compressed by the reciprocation of the pistons in the cylinders and stored in a suitable tank for use later, to be readmitted to the cylinders to operate the pistons and thus start the driving shaft into operation. A valve mechanism was employed for controlling the circulation of air and provision was made for securing such a high compression of air that when desired the air thus compressed would act as a pneumatic cushion and have sufficient resistance when so compressed to transmit the power which it received from the pistons to the cylinders, thereby causing the cylinders to revolve at the same speed as the pistons and thus drive the driven shaft at the same speed with the driving shaft. In addition to these functions the device was also capable of many other functions, any of which could be brought into play by adjusting the valve mechanism and by the operation of two foot pedals. One foot pedal was utilized to control the reverse and the other foot lever was connected directly to a band brake by means of which the bodily rotation of the cylinders could be prevented, which was necessary in coöperation with the valve mechanism to produce certain functions.

In the present application my object is to simplify the arrangement of the controlling mechanism and accomplishing the various functions so that it will be simpler for the operator and will also obviate the employment of manual energy in operating the band brake or the reverse, in the present case the mechanism being provided for operating the band brake and reverse by compressed air so that the only energy required of the operator is the slight amount necessary to shift a valve into various positions.

In carrying out my invention I employ a

setting valve and an operating valve, both of which are controlled by the operator, and a further object of the invention is to provide for the brake being applied by either valve irrespective of the position of the other valve, so that in cases of emergency if the operator should become confused, he could instantly apply the brakes by operating either of the valves. It is thus impossible for either valve to be in any position which would prevent the immediate application of the brake.

Another object of the invention is to provide a construction such that when the valve is placed in position for starting the engine it automatically applies the brake so that the vehicle is held stationary while the engine is being started. This relieves the operator from the necessity of thinking to apply his brake before he attempts to start the engine.

Other objects and advantages of the present invention will be brought out in the following description.

Referring to the drawings: Figure 1 is a plan view of the wheels, axles and frame of an automobile equipped with the invention. Fig. 2 is a section on line x^2-x^2 Fig. 1, on an enlarged scale. Fig. 3 is a vertical section on line x^3-x^3 Fig. 1. Fig. 4 is an enlarged section on line x^4-x^4 Fig. 1. Fig. 5 is a section on line x^5-x^5 Fig. 4. Fig. 6 is an enlarged section of the automatic check valve shown in section in Fig. 4 and taken on the same plane as the section in Fig. 4. Fig. 7 is a section on line x^7-x^7 Fig. 4. Fig. 8 is a plan view of the hand operated valve. Fig. 9 is a perspective view of the foot lever control and valve operated thereby. Fig. 10 is a perspective of a crank on a reduced scale. Fig. 11 is a perspective of the shift rod. Fig. 12 is an enlarged section on line $x^{12}-x^{12}$ Fig. 8. Fig. 13 is a section on line $x^{13}-x^{13}$ Fig. 12. Fig. 14 is a diagrammatic view of the conical hand valve and its conical seat, and the conical foot valve and its conical seat. The hand valve and its seat are shown at the left in the figure and the foot valve and its seat are shown at the right in the figure. In the hand valve the plug is in the center and its seat is represented as the outer circular portion. The same is true of the foot valve. The concentric dotted lines in the plug of either valve correspond to the same levels of the seat so that the angular

position of the plug with respect to its seat is apparent at a glance, and the corresponding levels can be easily compared. The connections extending between the two valves 5 diagrammatically represent the various air passages between the valves. All of the ports are shown in their exact angular positions. In this figure the position shown is that in which the driving shaft and engine are 10 running idle without compressing air or without imparting movement to the vehicle, the air simply circulating into the cylinders and out again, freely. Fig. 15 is a view similar to Fig. 14, showing the position of the parts 15 set for allowing air to pass from the reservoir into the cylinders to operate the driving shaft and start the engine. Fig. 16 is a view similar to Fig. 14, showing the valves set to allow the car to run forward under 20 momentum and hold the cylinders against rotation, thereby starting the engine. Fig. 17 is a view similar to Fig. 14, showing the position of the valves set for operating the car ahead, under the air pressure. Fig. 18 25 is a view similar to Fig. 14, showing the valves set for applying the brake. Fig. 19 is a view similar to Fig. 14, showing the valves releasing the brake. Fig. 20 is a view similar to Fig. 14, showing the valves set to apply 30 the band brake and reverse, killing the engine and causing sudden piling up of air pressure to brake the car in an emergency. Fig. 21 is a section on line $x^{21}-x^{21}$ Fig. 12. Fig. 22 is a section on line $x^{22}-x^{22}$ Fig. 12. Fig. 23 is a section on line $x^{23}-x^{23}$ Fig. 12. Fig. 24 is a section on line $x^{24}-x^{24}$ Fig. 12. Referring to Fig. 1, 1 designates an automobile frame with driving wheels 2 and brakes 3 on the driving wheel connected by 40 rods 4 with arms 5 projecting from a rock shaft 6. On the rock shaft 6 is an arm 7 with a pin 8 which engages in a slot 9 formed in a piston rod 10 which is operated by a piston 11 in a brake cylinder 12. 13 is 45 the motor with driving shaft 14. 15 designates the pneumatic power transmitter, 16 the driven shaft and 17 the storage tank for compressed air. 26 is a brake band which encircles the cylinder member 15 of 50 the pneumatic power transmitter, as clearly shown in Fig. 4, so that when suitable connection are operated, the brake band 26 will prevent rotation of the cylinder member 15 of the pneumatic transmitter, as later described. 19 designates a pedal for operating the brakes 3. When the pedal 19 is operated it pushes the rod 27 rearwardly which moves arm 7 forwardly, pin 8 traveling freely forward in the slot 9 and in slotted 55 arm 7, and shaft 6 is thus rocked which moves forward arms 5 and draws rods 4, thus operating brakes 3.

The pneumatic power transmitter comprises in the present embodiment a fly-wheel 30 which is formed with three cylinders 31

and with a central circular crank chamber 32 to which is attached a disk 33 on the end of a driving shaft 34. Secured to the other side of the crank chamber 32 is a cap 35 which is formed with a hub 36 in which is 70 mounted one end of the driven shaft 37, on the end of which is a crank 38 with counter-balance 39, the crank 38 being connected by a crank pin 40 with a crank 41 journaled on a boss 42 projecting from the 75 end of the driving shaft 34 and also provided with a counterbalance, the crank 41 being detachably secured to the crank pin 40 by screws 43.

Sliding in the cylinders 31 are trunk pistons 44, each of which has a connecting rod 45 which is connected with the crank pin 40.

Inserted in the fly-wheel 30 and flush therewith at the end of each cylinder is a plate 46, each of which has a rock valve 47 and is provided with a valve chamber 45, as clearly shown in Fig. 4, each valve 47 having an arm 49 which is connected with a rod 50.

Mounted on the driven shaft 37 is an 90 eccentric 51 and an eccentric strap 52 with which the rods 50 are pivotally connected, so that as the eccentric is operated by the shaft 37 the rock valves 47 will be oscillated through their connections with the eccentric. 95

As in certain functions the valves 47 are to be reversed, I provide a mechanism for reversing the eccentric 51. This consists of a pin 53 in the end of a rod 54, the latter being slidable in the center of the driven shaft 100 37, the pin 53 engaging spiral grooves 55 formed in the hub of the eccentric 51, so that when the rod 54 is moved longitudinally, the pin 53 sliding in the grooves 55 will turn the eccentric 51 and reverse the 105 position of the valves 47. The rod 54 is operated by a grooved disk 56, shown in detail in Fig. 11, to which the rod 54 is attached, the disk 56 having two openings 57 which slidably engage bars 58 of a universal joint 59 which prevents the disk 56 from turning with respect to the shaft 37. As a safety to prevent excessive compression in the cylinder, a valve 47' is formed in port 46', of each plate 46, see Fig. 4. Port 110 46' connects valve 47 with the cylinder.

The crank chamber 32 is airtight, thus forming an air chamber, and extending along the side of each cylinder 31 is an air passage, the inner end of which communicates with the interior of the crank chamber 32, the outer end of each air passage 62 communicating with the valve chamber 48. On the other side of each cylinder is an air passage 63, the inner end of which joins an air passage 63' formed in the cap 35, as clearly shown in Fig. 7, the passage 63' communicating with an annular chamber 64 formed in the cap 35 and having ports 65 which extend from the chamber 64 120 125 130

to a hollow ring 66 which encircles the hub 36, and the ring 66 is held in position by a collar 67 which is screwed on the hub 36.

Extending from the hollow ring 66 is a pipe 68 which as shown in Figs. 1 and 7, extends to a valve casing 69. The valve casing 69 contains two valves viz., a hand valve 70 and a foot valve 71, these valves being shown in detail in Figs. 12 and 13, and the connections for operating them being shown in Figs. 1 and 9.

Referring to Figs. 12 and 13, the hand valve 70 and foot valve 71, have passages disposed at different levels or elevations.

These successive levels are indicated in Fig. 12 as *a'*, *b'*, *c'* and *d'*. The levels in the casing of the valve corresponding to these elevations are *a*, *b*, *c* and *d*. The hand valve 70 has passages 73 and 74, and segmental 20 passages 75 and 76. The passages 75 and 76 are on the level *d* of the valve 70, see Fig. 24. Passage 75 is also connected at one end to level *c'*. The foot valve 71 is provided with segmental passages 78 on level *a*, see Fig. 22; 77 and 79 on level *b'*, see Figs. 21 and 91 on level *c'*, see Fig. 23, one end of passage 91 being also connected to level *b'*. Radial passages 80 on level *a'*; 81 on level *c'*; 82 on level *d'*, connect with a manifold 30 passage 83, see Fig. 12. The casing of the valve is provided with passages at various levels. Thus in connection with hand valve 70, passage 75' is on the *b* level and communicates with passage 95. In the casing

35 on the *d* level, see Fig. 24, are passages 86 and 84, 86 extending to level *c* on foot valve 71, see Fig. 23, and 84 extending to level *b* see Fig. 21, on valve 71. Passage 86' connects passage 86 with pipe 113, thus providing communication with brake cylinder 12. Passages 88' on level *c*, see Fig. 23, and 88 on level *b*, see Fig. 21, communicate with passage 95. Passage 85 on level *c* communicates with pipe 104, and thence to band

40 brake 26. Passage 87 on level *b* communicates with pipe 101, and thence to reverse cylinder. Passage 89 on level *d* connects passage 85 with a point annularly positioned to communicate with port 82 when foot

50 valve 71 is in neutral position. Passage 90 on level *c* communicates with a point annularly positioned to communicate with passage 81 on foot valve 71 when same is in neutral position. Passage 83' on level *a* connects passage 92 with a point annularly positioned for connection with passage 80 of foot valve 71 when same is in neutral position. It should be understood that all passages formed in the casing make communication

55 with other passages only at their extremities, or where they come to the surface. The casing also has a spring pressed check valve 97 which normally closes communication between passages 93 and 96. A pipe 98 leads from the passage 92 to a muffler 99,

thence communicating with the atmosphere. A pipe 100 leads from the passage 95 to the storage tank 17. A pipe 101 leads to a reversing cylinder 103, see Fig. 1. A pipe 104 leads to a band brake cylinder 105, see Fig. 1. As shown in Fig. 3 the band brake cylinder contains a piston 106 which has a piston rod 107 pivotally connected with two bell crank levers 108, each pivoted at 109 and connected to opposite ends of the band 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 Operation.

125

Engine running idle, car standing still.—With the foot lever in central or neutral position, and with the hand valve adjusted as shown in Fig. 14, the cylinders are in 130

communication with the atmosphere, air circuit being traced as follows: from muffler 99 to pipe 98, through passage 92 and passage 73 in hand valve 70, through passage 5 93 to pipe 68 to collecting ring 66, through passages 65 and 64 and 63' and 63 to the cylinders, so that with engine running, air which is sucked into the cylinders 31 will be expelled through the muffler. Air in 10 tank 17 cannot escape through pipe 100 and passage 96 because the pressure of air holds valve 97 closed. In this position ports 89 and 90 are in communication with ports 82 and 81, the latter ports being connected 15 to manifold passage 83. The port 80 leading from said passage 83 communicates with passage 83', thence to muffler and atmosphere. Thus in this position of the valve the reverse cylinder and band brake cylinder 20 are on the exhaust. Port 84 is likewise in communication with port 77 which, by passage 83, 80 and 83' leads to muffler and atmosphere. Thus, with valve in neutral position, the car brake may be exhausted by 25 hand valve 70 as hereinafter explained.

Running car forward by engine.—To cause the automobile to be propelled forward the hand valve 70 is turned from the position shown in Fig. 13 to close port 93, 30 (this position not being shown in any of the views) and with port 93 closed, and the car standing still, rotation of the engine shaft 34 will rotate the cylinders and cause relative reciprocation of the pistons therein, 35 thereby compressing air and forcing the same from collecting ring 66 through pipe 68 into passage 93, the air thus compressed accumulating pressure until it overcomes valve 102 and flows into the tank until the 40 pressure in the tank is sufficient to balance the pressure in passage 93 and pipe 68, whereupon the resistance of the compressed air in these passages locks the piston from further reciprocation in the cylinders and 45 thereby rotates the driven shaft in unison with the cylinders, thus driving the car forward.

Starting engine by compressed air, with car standing still.—The foot and hand 50 valves are swung into position shown in Fig. 15, whereupon air circuits are as follows: Air from the tank passes through pipe 100 and passage 95, thence through port 88. In Fig. 15 port 88 is seen to be 55 on circular dotted line *b* which is on the same level with dotted line *b'*, and being in the same angular position communicates with port 79, thence around on dotted lines to indicate that it is sunken below the surface so as to not have communication with any other ports which may be at this level during other angular positions. The other end of the port 79 is in angular position 60 with port 87 and the latter is on the same level, being on dotted line *b'* and thus com-

municates therewith. From port 87 the circuit is through pipe 101 to reverse cylinder 103 which operates to reverse the valves 47. In addition to this, connection is also made through port 88' which is on the dotted line *c* at another level, thence through port 91; see Fig. 23, and port 86, thence through passage 86', and pipe 113 to brake cylinder 12, thus applying the brakes and holding the automobile stationary. Note that in Fig. 15 the port 88' lies behind the port 88 shown in the diagram, it being impossible to show both of these ports in the one diagram as they are both in the same angular position, but occupy different levels. Thus as air is admitted to the cylinders the latter being held stationary by the stationary automobile causes reciprocation of the pistons which are connected to the engine shaft, and the engine is thus rotated in the proper direction to start it. After the engine is thus started the valves may be restored to neutral position and if it is desired to propel the car forward, hand valve 70 may be moved to close port 93, see Fig. 13.

Applying air brake.—By moving hand valve 70 into position shown in Fig. 18, it brings port 75 into communication with port 75' thereby permitting air to pass from the tank through port 75, passage 75, port 86, 95 passage 86' and pipe 113 to brake cylinder 12, thereby applying the brakes. To release the brakes the hand valve is thrown from position shown in Fig. 18 to position shown in Fig. 19 which brings port 76 into communication with port 84 which is on the level *a*, communicating with port 77, port 83, port 80, see Fig. 12, to passage 83', thence to passage 92 and pipe 98 to muffler and atmosphere. The other end of port 76 communicates with port 86, passage 86', pipe 113 to 100 brake cylinder 12.

Running forward under air pressure.—Hand valve 70 and foot valve 71 are placed in the position shown in Fig. 17, whereupon air from the tank passes through passages 95, 88' and 91 on level *c'*, thence through pipe 104 to the band brake cylinder 105 thereby applying the band brake and arresting rotation of the cylinders. Air then enters from passage 95 to passage 74 to port 93 through pipe 68 to cylinders 31, thereby acting on the pistons therein to reciprocate the same and operate the driven shaft, thereby propelling the car forward under air 115 pressure.

To start engine when car is running forward under momentum.—The valves 70 and 71 are placed in the position shown in Fig. 16, whereupon air from tank passes from 120 passage 95 through passage 88 to port 79, thence flows through port 79, a portion of which is shown by heavy dotted lines in Fig. 16, as a continuation of that portion 125 which is shown in shaded black, and is 130

located on lever b' . From port 79 it goes to passage 87, thence through pipe 101 to reverse cylinders 103, thereby reversing the valves 47. Air is admitted from passage 95 to passage 74 in hand valve 70, thence through passage 93 and pipe 68 to the cylinders, thereby causing a rapid piling up of air against the pistons in the cylinders which reacts on the cylinders as the pistons are kept moving forward by the momentum of the car and the reaction of the pressure of the air in the cylinders against the cylinders starts the engine, which movement is in the proper direction to start the engine as the valve had been moved to reverse position.

Applying emergency brake.—The valves are placed in the position shown in Fig. 20 which permits the air to flow from passage 95 to passage 88' through passage 91, thence to port 86 through pipe 104 to hand brake, thereby arresting the movement of the cylinders 31, also air from port 91 passes into port 87, thence through pipe 101 to the reverse, thereby reversing the valves in the cylinders. The cylinders having been arrested and the valve 31 therein reversed, hand valve is moved to a clutching position to cut off port 93, whereupon the forward motion of the automobile will cause a sudden compression of air in the cylinders by reason of the latter having been arrested from rotation, and this sudden compression of air in the cylinders brings the car to a sudden stop.

In all the positions of the foot valve 71, except when starting engine by compressed air, with car standing still, passage 84 is in communication with passage 77, the latter being in communication with atmosphere by passage 83, port 80 and passage 83, or by passage 77, 78, and 83'. Thus in any of the operations, excepting the one noted, it is possible to operate the car brakes by hand valve 70, exhausting through foot valve 71. In the operation of starting the engine by compressed air, it is necessary for car brakes to be held, so it is impossible to exhaust by hand valve 70, there being no communication of ports 84 and 77 as shown in Fig. 15.

What I claim is:

1. A driving member, a driven member, cylinders connected with one of said members, pistons in the cylinders and connected with the other member, valves for controlling the circulation of air in the cylinders, a tank in communication with said valves, a fly-wheel carrying said cylinders, a brake band on the fly-wheel, a cylinder with a piston therein connected with said brake band and a controlling valve adjustable to admit air from said tank into said cylinder and into said first cylinders.

65 2. A driving member, a driven member,

cylinders connected with one of said members, pistons in the cylinders and connected with the other member, valves for controlling the circulation of air in the cylinders, a tank in communication with said valves, and a brake for controlling the rotation of the cylinders, a cylinder with a piston therein, means operated by the latter piston for controlling the position of said valves and valve mechanism for admitting air from said tank to said brake cylinder and said first cylinders.

3. A driving member, a driven member, cylinders connected with one of said members, pistons in the cylinders and connected with the other member, valves for controlling the circulation of air in the cylinders, a storage tank, a controlling valve communicating with the respective cylinders and storage tank and atmosphere, said controlling valve having ports and adjustable to place the cylinders in communication with the storage tank, or the cylinders in communication with the atmosphere, or shut off the foregoing cylinder communication, pneumatic means for preventing rotation of the cylinders, said controlling valve also having ports adjustable to place said pneumatic means in communication with the storage tank to cause stoppage of rotation of the cylinders.

4. A driving shaft, a driven shaft, cylinders carried by one of said shafts, pistons in the cylinders connected to the other shaft, a storage tank, pneumatic means for arresting the movement of said cylinders, valves for controlling the circulation of fluid through said cylinders, pneumatic means for controlling said valves, a setting valve provided with ports for placing said cylinders in communication with said tank or either of said pneumatic mechanisms in communication with said tank, and an operating valve for controlling admission of air to the setting valve.

5. A driving shaft, a driven shaft, cylinders carried by one of said shafts, pistons in the cylinders connected to the other shaft, a storage tank, pneumatic means for arresting the movement of said cylinders, valves for controlling the circulation of fluid through said cylinders, pneumatic means for controlling said valves, a setting valve provided with ports for placing said cylinders in communication with said tank or either of said pneumatic mechanisms in communication with said tank, and an operating valve for controlling admission of air to the setting valve, said setting valve also having ports for controlling the passage of air from the storage tank to said first pneumatic means.

6. A driving shaft, a driven shaft, cylinders carried by one of said shafts, pistons in the cylinders connected with the other shaft,

a storage tank, pneumatic means for arresting rotation of said cylinders, valves for controlling the circulation of fluid through said cylinders, pneumatic mechanism for controlling said valves, a setting valve for controlling the circulation of air between said cylinders and tank or between said tank and either of said pneumatic mechanisms, a foot lever, connections from said foot lever to 10 said setting valve, and an operating valve for controlling the air circuit through said setting valve.

7. A driving member, a driven member, means operated by relative movement between said members for compressing air, storage means for compressed air, braking means for one of said members, pneumatic means for operating said braking means, and a controlling valve for admitting air 20 from said storage means to said compressing means and to said braking means.

8. A driving member, a driven member, means operated by the relative movement of said members for compressing air, air storage means, valves for controlling the circulation of air in said compression means, a controlling valve communicating with said compression means, and storage tank and atmosphere, said controlling valve having 25 ports and being adjustable to place said compression means in communication with the storage tank, or in communication with the atmosphere and shut off said compression means from the storage tank, pneumatic means for preventing the operation 30 of said compression means, said controlling valve also having ports adjustable to place

said pneumatic means in communication with the storage means.

9. A driving shaft, a driven shaft, air compression means operated by relative movement between said shafts, a storage tank, pneumatic means for arresting the movement of said air compression means, valves for controlling the circulation of fluid through said air compression means, pneumatic means for controlling said valves, an air brake, a setting valve provided with ports for placing said air compression means in communication with said tank, or either 50 of said pneumatic mechanisms in communication with said tank, or said air brake in communication with said tank, and an operating valve for controlling admission of air to the setting valve. 55

10. A driving shaft, a driven shaft, means operated by the relative movement between said shafts for compressing air, means for storing said air, means operated by air from said storage tank for starting the driving shaft, braking means for preventing rotation of the driven shaft and a valve for admitting air to said starting means to start the driving shaft and for automatically admitting air to said brake to automatically 60 apply the same. 65

In testimony whereof, I have hereunto set my hand at Los Angeles Cal. this 19 day of October, 1911.

FRANK M. PRATHER.
